UNITED STATES PATENT OFFICE.

CHARLES C. FREEMAN, OF DIXFIELD, MAINE.

MACHINE FOR BOXING TOOTHPICKS.

No. 906,214.

Specification of Letters Patent.

Patented Dec. 9, 1908.

Application filed February 23, 1907. Serial No. 358,784.

To all whom it may concern:

Be it known that I, CHARLES C. FREEMAN, a citizen of the United States, residing at Dixfield, in the county of Oxford, State of Maine, have invented a certain new and useful Improvement in Machines for Boxing Toothpicks, of which the following is a specification, reference being had therein to the accompanying drawings.

10 My present invention relates especially to machines for filling boxes with tooth picks, but may be employed for other similar articles.

In general, it is of the type shown in my 15 previous application filed February 12, 1907, Serial No. 357,183, to which reference may be had, if desired.

My present invention relates especially to an improvement in the means for measuring 20 the number of tooth picks to be contained in the box or other receptacle and to the means directly employed for placing the tooth picks in the box.

The invention will be fully understood 25 from the following description taken in connection with the accompanying drawings, and the novel features are pointed out and clearly defined in the claims at the close of the specification.

30 Referring to the drawings,—Figure 1 is a side elevation of a machine embodying my invention. Fig. 2 is an elevation partly in section on line 2—2 of Fig. 1, and also showing in elevation the operating means for the 35 bottom receptacle for the purpose of illustrating the opening mechanism in connection with the rotating member. Fig. 3 is a section on line 3—3 of Fig. 2. Fig. 4 is a side elevation of the measuring device showing 40 the leaves of the bottom receptacle open to discharge the picks into the box. Fig. 5 is a detail of the guard.

Referring now to the drawings and more particularly to Fig. 1,—there is indicated at 45 A the frame work of the machine; at B the chute down which the picks come from the tumbling machine; and at C is shown the distributing wheel by means of which the picks are spread out and deposited in the cur- 50 tained receptacle D from which they fall into the chute E. The picks slide down the chute E into the upper evening receptacle F where they are all caused by means of the follower G to lie parallel and adjacent to each other 55 without projecting one beyond another. At H is indicated the lower evening receptacle

into which the upper evening receptacle F dumps.

The parts thus far described are the same in construction and operation as those de- 60 scribed in my application hereinbefore re-ferred to, and form no part of the present in-vention, except as the elements enter into combination with the parts which will hereinafter be described.

65 The lower evening receptacle H dumps into a chute 11 which is of a width slightly in excess of the length of the pick. In this chute the picks lie crosswise instead of lengthwise, as was the case with regard to the 70 chute E previously referred to. At the bot- 75 tom of the said chute 11 is the measuring wheel 12 provided about its periphery with pockets 13 of any desired size. The pockets 13 are preferably in groups, each group being capable of containing only the number of 80 picks which it is desired to place in a box. In the drawing, there are shown two groups of pockets, in each group of which there are four pockets, the said four pockets together having a capacity equal to that of the box 85 15. About the said measuring wheel 12 is placed a casing 16 which does not permit the pockets to discharge their picks until the de-sired point in the rotation of the wheel is reached.

In order that each pocket 13 shall be filled exactly full and that no picks shall be jammed between the casing and the measuring wheel, I provide a knurled wheel 17 mounted on a 90 shaft 18 and driven by a belt 19 from the main driving shaft 20, upon which the meas- 95 uring wheel 12 is mounted. The said knurled wheel 17 has a somewhat greater surface speed than the surface speed of the measur-ing wheel 12 and rotates in the direction indi-cated by the arrow in Fig. 2, so that any 100 picks which might otherwise be jammed be-tween the said casing and the said measuring wheel are thrown back from the point of en-gagement between the casing 16 and the pe- 105 riphery of the measuring wheel 12. As seen in Fig. 3, the said knurled wheel is provided with a number of grooves 21 for the reception of guards or fingers, so that there may be no 110 chance of picks getting caught by the knurled wheel or being thrown away from it into the other parts of the mechanism. In the drawings, I have shown these guards for the knurled wheel in the form of an upper guard attached to the frame of the machine and a lower guard attached to the casing of

the measuring wheel. The upper guard consists of three depending fingers 22, see especially Figs. 2 and 5, which are bent backward slightly to conform to the portion of the 5 groove 21 with which they coöperate. The lower guard consists of three similar fingers 23 fastened to the casing 16 and nearly meeting the ends of the fingers 22 just referred to. It will be seen that by this arrangement of 10 the upper and lower guards, there is no possibility of any of the picks being carried around the knurled wheel or being carried into the crevice between the measuring wheel 12 and the casing 16. The upper guard is adjustable 15 slightly with relation to the lower guard by means of a pair of slots 24 in the plate 25 to which the fingers 22 are soldered. These slots are engaged by screws 251 by means of which the guard is attached to the frame of 20 this part of the machine.

Attached to the plate 25, just referred to, is a U-shaped projecting piece 26, the bottom of which engages the picks in the chute 11 and keeps them from passing into the pockets in the measuring wheel in too great quantities which would tend to cause displacement of the picks from their horizontal position or might disturb their parallelism.

Having now described the means by which 30 the pockets 13 in the measuring wheel 12 are filled, the mechanism by means of which the picks are transferred from the pockets to the box will now be described. At the bottom of the casing 16 is an opening 27 through 35 which the picks in the pockets 13 drop when the pocket 13 comes in registration with the said opening 27. A V-shaped receptacle, substantially similar to the receptacle H heretofore referred to, receives the picks as they fall from the pockets 13. This V-shaped receptacle is formed by two slanting sides or leaves 29 and 30 pivoted at 31 and 32 to the casing 16 and a pair of V-shaped ends 33 attached to the casing 16. Said V-shaped 40 ends 33 are fixed while the leaves 29 and 30 are movable about the said pivots 31 and 32 by means of the lever arms 35 and 36 and the intermediate link 37. A spring 38 attached to any suitable fixed point tends to maintain 45 the parts in the closed position. The parts in their open position are shown in Fig. 4.

The parts thus described are operated by means of one or more projections on the surface of a wheel 34 on the shaft 20. In the 55 drawings, I have shown these projections as screws 39, that being a convenient form of construction. The said screws 39 are so placed on the wheel 34 that one of them will contact with the upper end of the arm 36 to 60 open the receptacle just as soon as the last pocket 13 of one of the groups of pockets has discharged its picks into the said receptacle. The other of the said projections 39 performs the corresponding operation to discharge the 65 picks which the other group of pockets has

emptied into the receptacle. This operation will be clearly seen in Fig. 4, where one of the projections 39 is in contact with the arm 36 and the receptacle is opened to substantially the full extent.

What I claim is:

1. In a boxing machine, a rotating member having pockets therein in groups to receive and transfer the material to be boxed, means for delivering the material to said 75 pockets, a receptacle into which the material is discharged from said pockets after a partial rotation of said rotating member, said receptacle having a hinged portion which may be opened to discharge the contents thereof, 80 and mechanism controlled by the movement of said rotating member, whereby said hinged portion is opened after all the pockets in a single group have discharged their 85 contents into said receptacle.

2. In a machine for boxing tooth picks, a rotating member having peripheral pockets therein in groups, said pockets extending parallel with the axis of said rotating member, means for delivering tooth picks to said 90 pockets so that they shall lie in said pockets parallel to each other and parallel to the axis of said rotating member, means for retaining the tooth picks in said pockets during a partial rotation of said rotating member, a receptacle into which each pocket discharges at 95 a certain point in the rotation of said member, said receptacle having a hinged portion which may be opened to discharge the contents thereof, mechanism connected with said hinged portion for opening the same, and mechanism carried by said rotating member which actuates said opening mechanism after all the pockets in one group have moved past said discharge receptacle.

3. In a machine for boxing tooth picks, a rotating member having peripheral pockets therein in groups, said pockets extending parallel with the axis of said rotating member, means for delivering tooth picks to said 100 pockets so that they shall lie in said pockets parallel to each other and parallel to the axis of said rotating member, means for retaining the tooth picks in said pockets during a partial rotation of said rotating member, a receptacle into which each pocket discharges at 105 a certain point in the rotation of said member, said receptacle having one or more pivoted sides which may be opened to discharge the contents thereof, mechanism connected with said pivoted sides for opening and closing the same and mechanism carried by said 110 rotating member which actuates said opening mechanism at certain periods in the rotation of said rotating member after all the 115 pockets in a single group have passed and discharged their contents into said receptacle.

4. In a machine for boxing tooth picks, a rotating member having parallel pockets 120

therein in groups to receive and transfer the tooth picks, means for delivering tooth picks to said pockets so that they shall lie therein parallel to each other, a receptacle into which 5 the picks are discharged from said pockets after a partial rotation of said rotating member, said receptacle having one or more pivoted sides which may be opened to discharge the contents thereof and mechanism controlled by the movement of said rotating member whereby the pivoted sides of said discharge receptacle may be opened after all 10 the pockets in a single group have discharged their contents into said receptacle.

15 5. In a machine for boxing tooth picks, the combination of a receptacle to contain a supply of tooth picks a rotating member having one or more pockets therein to receive and transfer picks from the supply in said receptacle a rotating clearing wheel coöperating therewith and having an annular groove in its periphery and a stationary clearing finger in said groove.

6. In a machine for boxing tooth picks, the 25 combination with a receptacle containing a supply of picks, of a rotating member having one or more pockets therein to receive and transfer a predetermined number of picks from said supply in said receptacle, a coöperating clearing member and a fixed U-shaped guard for checking the flow of picks passing in the receptacle to the pockets of the moving member.

7. In a machine for boxing tooth picks, a 30 35 rotating member having a plurality of pock-

ets therein to receive and transfer a predetermined number of picks, means for supplying tooth picks to the pockets in said rotating member in parallel relation to each other and parallel with the axis of said rotating member, a coöperating clearer to remove the surplus picks from each pocket, a receptacle into which the picks are discharged from the pockets of said rotating transfer member and mechanism controlled by said rotating transfer member whereby the said receptacle is opened at a predetermined point in the rotation of said transfer member to permit the discharge of the contents of said receptacle. 40 45

8. In a machine for boxing tooth picks, a 50 rotating member having therein a series of pockets having all together the capacity to contain the number of picks required to be placed in a box, means for supplying picks to said pockets and delivering them thereto in 55 parallel relation with each other, a coöperating clearer for removing the surplus picks from each pocket, a receptacle into which the pockets of the said rotating member are discharged and means controlled by said rotating member to open the said receptacle after all the pockets in a series have discharged their contents into said receptacle. 60

In testimony whereof I affix my signature, in presence of two witnesses.

CHARLES C. FREEMAN.
